UNITED STATES PATENT OFFICE.

DAVID MICON, OF BENTON HARBOR, MICHIGAN.

MATTRESS.

1,211,475.

Specification of Letters Patent.

Patented Jan. 9, 1917.

Application filed June 28, 1915. Serial No. 36,671.

To all whom it may concern:

Be it known that I, DAVID MICON, a citizen of the United States, residing at Benton Harbor, in the county of Berrien and State 5 of Michigan, have invented certain new and useful Improvements in Mattresses, of which the following is a specification.

This invention relates to mattresses and has for its object the provision of a mattress, which is free from the objectionable features which characterize all mattresses heretofore in use.

In the construction of mattresses as ordinarily made prior to my present invention 15 the tick is filled with felt, hair or other suitable filling material and the top and bottom are then sewed together through the filling, suitable buttons or tufts being attached to threads outside the tick, to compress the 20 filling. This sewing is accomplished by means of a long three-cornered needle having sharp edges which cut the threads of the tick fabric, making an unsightly hole which will enlarge as the fabric stretches in use 25 and should the tufts or buttons be detached, as usually occurs after a time, the thread will enlarge the holes until it finally pulls through the fabric, leaving an opening through which dirt and vermin may readily 30 reach the interior of the mattress. Furthermore, the roll edge, which is now generally provided on mattresses is formed by sewing with a large needle and coarse thread across the edge of the mattress through the filling, 35 resulting in additional holes and an uneven appearance of the edge and boxing of the mattress even when the most skilful mattress-makers are employed. My invention overcomes these and other objectionable features of mattresses as usually constructed by 40 strengthening the fabric so that no stretching is possible; by providing means whereby the top and bottom of the tick are secured together to compress the filling without sewing 45 through the tick and filling in the usual manner, thus eliminating all unsightly holes and the necessity of employing buttons or tufts; and by providing separate compartments along the edges of the mattress which, 50 when filled, produce the desirable roll edge.

My invention and its numerous objects and advantages will be better understood by reference to the following specification, when read in connection with the accompanying drawing in which—

Figure 1 is a perspective view of a portion

of a finished mattress; Fig. 2 is a vertical section on the line 2—2 of Fig. 1; Fig. 3 is a vertical section on the line 3—3 of Fig. 1, and Fig. 4 is a plan view disclosing the 60 means for reinforcing the top and bottom of the tick as well as the arrangement of the loops and of the flaps forming the corner compartments.

Referring to the drawing, 1 indicates the 65 top, 2 the bottom and 3 the sides of the tick, which may be filled with any suitable material 4, such as felt, hair, etc. The tick is reinforced both longitudinally and transversely by a plurality of intersecting strips 50 5 stitched to the inner sides of the top and bottom. At the intersections of the strips 5 loops 6 are secured, the ends of the loops being preferably disposed beneath the strips 5 and secured by the stitching which secures 55 the strips 5 to the top and bottom of the tick. The loops 6 are so positioned on the top and bottom as to be oppositely disposed when the tick is assembled and filled, and each pair of loops 6 is connected by suitable 60 connecting means which preferably consists of the twine 7 passing through the loops 6 at the bottom and knotted, as indicated at 8, through the loops 6 at the top.

I provide the roll edge on the mattress by 65 securing the flaps 9 to the top and bottom, the top and bottom being preferably looped inwardly, as indicated at 10, so that the stitches are not exposed. The opposite edges of the flaps 9 are stitched to the sides 3 at 70 90 11 and, as will be apparent from an inspection of the drawing, when the edges of the top and bottom, respectively, and the sides are stitched, as indicated at 12, separate compartments 13 are formed along the edges 95 of the mattress which may be filled with any suitable material after the body of the mattress is completed.

In the manufacture of a mattress according to my invention the filling, which may 100 consist for example of layers of felt, is placed on a table of suitable size to accommodate the mattress and the assembled tick is turned wrong side out and slipped over the end of the filling until the first row of 105 loops 6 is reached. The operator then passes a needle (not shown) having a hook formed adjacent one end thereof through the filling, advancing the needle slightly in order that the filling may be drawn backward and after 110 engaging the twine 7, which is already disposed through the lower loop 6, draws it

upwardly and knots it through the upper loop 6, first drawing the top and bottom of the tick together to compress the filling. The tick is then drawn forwardly over the filling until the next row of loops is reached when the operation is repeated. When the final row of loops has been connected the side 3, forming the open end of the mattress, is drawn upwardly over the end of the filling and the body portion of the mattress is completed by sewing together the edges of the flaps 14 (see Fig. 3), corresponding to the flaps 9 previously described, two flaps being provided at this corner of the mattress, however, to facilitate the final sewing thereof. In this connection it will be apparent that the mattress tick must be open at one end in order that it may be slipped over the filling and that the roll edge at the corner of the mattress which is left open must be finished after the mattress has been filled. Consequently the flap 14 at this corner of the mattress is divided longitudinally forming two flaps, as indicated in the drawing, which are sewed together after the mattress has been filled. The reason for this construction will be apparent when it is understood that the tick is manufactured complete, being stitched on machines before it is filled, and the form and appearance of the mattress depend largely on the regularity of the stitching. By providing the two flaps 14 applicant is enabled to close the mattress, drawing it tightly about the filling and stitching it by hand at a place where the stitching is concealed so that the appearance of the stitching is of no consequence. The edges of the top and side are sewed at 12, as previously described, and the separate compartments along the edges of the mattress are filled in any suitable manner, after which the corners may be sewed and the mattress completed.

It will be readily understood from the foregoing description that I have devised a mattress in which the means for securing the top and bottom together and compressing the filling is disposed entirely within the tick and that hence there is no necessity for sewing through the tick in accordance with the common practice and hence no dirt-collecting openings in the tick result. The surface of the mattress presents an even appearance and there are no tufts or buttons to be lost nor is there any possibility of the thread tearing through the tick and releasing the filling. Furthermore, by providing separate compartments for the roll edge I obviate the necessity of sewing across the edge as has heretofore been customary and obtain a more even and lasting roll edge

without the exposed coarse stitching which has been a characteristic of previously known forms of roll edge mattresses and which frequently tears the tick. Finally, 65 mattresses may be constructed in accordance with my invention by unskilled operators which will present a better appearance than mattresses of previously known forms constructed by the most skilled mattress-makers. 70

It will be apparent that various changes may be made in the form, construction and arrangement of the parts without departing from the spirit and scope of the invention or sacrificing any of its material advantages, 75 the form hereinbefore described being merely preferred embodiments thereof.

I claim:

1. A mattress comprising a tick having a top, bottom and sides and a continuous solid filling therefor, and means disposed entirely within said tick secured to said top and bottom at points spaced longitudinally and transversely thereof and passing through said filling, whereby said top and bottom 85 may be secured together to compress said filling.

2. A mattress comprising a tick having a top, bottom and sides, and a continuous solid filling therefor, reinforcing means secured to the inner sides of said top and bottom and extending longitudinally and transversely thereof, and means disposed entirely within said tick secured to said top and bottom at the intersections of said reinforcing 95 means and passing through said filling, whereby said top and bottom may be secured together to compress said filling.

3. A mattress comprising a tick having top, bottom and sides and a continuous solid 100 filling therefor, a plurality of intersecting strips secured to the inner sides of said top and bottom to reinforce the same longitudinally and transversely, a plurality of loops secured to said top and bottom at the intersections of said strips, and means passing through said filling for connecting said loops.

4. A mattress comprising a tick having a top, bottom and sides and a filling therefor, 110 and a plurality of flaps disposed across the corners of said tick within the same and secured to said top and bottom respectively and to said sides to form separate compartments adapted when filled to provide a 115 roll edge, the flap along one edge of the mattress being divided longitudinally to facilitate the filling and closing of the mattress.

DAVID MICON.
